Primary Examiner — Catherine S Posthauer*Assistant Examiner* — Crystal R Ponce*(74) Attorney, Agent, or Firm* — K&L Gates LLP(57) **CLAIM**

The ornamental design for a packaging container for battery, as shown and described.

DESCRIPTION

FIG. 1 is a perspective view of a packaging container for battery showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines depicted in FIGS. 1, 2 and 3 represent perforation lines which form a part of the claimed design.

1 Claim, 5 Drawing Sheets(56)
